UNITED STATES PATENT OFFICE.

THOMAS HORACE BOLAM, OF WEST EALING, AND SIDNEY NORMAN BARNARD, OF PUCKERIDGE, WARE, ENGLAND.

KINEMATOGRAPHIC APPARATUS.

1,076,404.

Specification of Letters Patent.

Patented Oct. 21, 1913.

Application filed August 12, 1910. Serial No. 576,856.

To all whom it may concern:

Be it known that we, THOMAS HORACE BOLAM and SIDNEY NORMAN BARNARD, both subjects of the King of Great Britain, residing, respectively, at 173 Uxbridge road, West Ealing, in the county of Middlesex, England, and South Road, Puckeridge, Ware, in the county of Herts, England, have invented certain new and useful Improvements in or Relating to Kinematographic Apparatus, of which the following is a specification.

This invention relates to kinematographic apparatus of the kind in which a large number of successive small photographs are taken in a helical path upon a sensitized flexible band from which, after developing and fixing, a positive is made and placed in the apparatus whereby the said photographs can be observed through a magnifying lens or projected onto a screen through a lens, while the flexible photographic band is being caused to travel in a helical path past the lens by suitable mechanism. With apparatus of this kind as heretofore proposed the flexible film or the like bearing the photographs has been used in the form of an endless band suspended loosely upon a rotary and laterally movable member/actuated by suitable mechanism so as to successively bring the photographs opposite the aforesaid lens.

According to this invention the photographic film or the like is affixed to a rotary cylinder or drum in such a manner that it is held tightly around said drum in a more or less rigid manner, and can be easily removed when desired. The said drum is provided with means for enabling it to be revolved intermittently at a predetermined speed by hand or by a suitable motor and with means whereby it also receives a longitudinal movement to an extent depending upon the pitch or inclination of the helically arranged photographs on the photographic film or the like. The drum is arranged within a box or casing which is capable of being closed in a light-tight manner, the said box or casing being provided with a lens through which the exposure of the sensitized film takes place when the apparatus is being used to take the photographs. Situated adjacent to the said lens is a rotary or other form of movable shutter

which is so arranged relatively to the mechanism employed for actuating the drum that it screens the lens during the intermittent movement of the drum and exposes said lens during the intervals between the intermittent movements, so that the exposure of the sensitized film only occurs while the drum is at rest. When the film or band on which the pictures or finished photographs are printed is mounted on or affixed to the drum and the apparatus used to obtain the kinematographic effect the photographs may be observed through a suitable magnifying lens detachably mounted on the box or casing, appropriate means being provided to direct the light on to the pictures as they pass the lens. If the photographs are required to be projected upon a screen, the said drum on which the "positive" film is mounted may be made of transparent material and an electric lamp may be situated within the drum so as to project the photographs through a lens or lenses suitably arranged in the apparatus.

In order that our said invention may be clearly understood and readily carried into effect we will describe the same more fully with reference to the accompanying drawings in which:—

Figure 1 is an elevation of the apparatus. Fig. 2 a part sectional plan of the same with the lid or cover removed, and Fig. 3 a cross sectional view on the line A. B. of Fig. 1. In these figures the apparatus is shown in condition for taking the photographs; Fig. 1^a is a face view of the rotary shutter employed for this purpose. Fig. 4 is a longitudinal section of the rotary drum illustrating one method of attaching the film to the said drum. Figs. 5 and 6 show a cross sectional view and a plan of a portion of the rotary drum and illustrate a modified method of attaching the film to the said drum. Fig. 7 is a detail view hereinafter explained. Fig. 8 is a plan and Fig. 9 a cross sectional view on line C. D. of Fig. 8, showing the apparatus when in condition for obtaining the kinematographic effect by observing the pictures or photographs through the magnifying lens. Fig. 8^a is a face view of the rotary shutter employed for this purpose. Fig. 10 is a diagrammatic view of the arrangement for obtaining the kinematographic effect by projecting the

pictures on to a small screen, and Fig. 11 is a plan of the transparent drum and the electric circuit for the illuminating lamp.

The drum *a* carrying the film *b* or the like is mounted on a shaft or spindle *c* situated in the box or casing *d*. The drum is adapted to be moved along said shaft in a longitudinal direction and at the same time to revolve around said shaft by suitable gearing *e* operated by a handle *f*. The box or casing *d* is provided with a lid or cover *d¹* hinged at *d²* and kept closed in a light tight manner by suitable spring clips *d³*.

The shaft *c* is provided at each end with a square or flat portion to fit into a square socket or support *c¹* situated at each end of the box *d*, so that said shaft is supported in a horizontal position. To prevent the shaft from rotating or moving in the sockets, retaining pieces *c²* pivoted at *c³* are provided which bear on each end of said shaft, and are held in this position by lugs *d⁴* on the inner side of the lid or cover *d¹* engaging the retainers *c²* when said lid is closed, as shown in Fig. 7. Each retainer *c²* may also be provided with a strut *c⁴* pivoted thereto at *c⁵*, which strut is adapted to hold the retainer in position when turned down to engage the side or wall of the box as shown by the full lines in Fig. 7, or can be moved to the position indicated by the dotted lines, to enable the shaft *c* to be lifted out of the box.

The drum *a* as shown in Figs. 4 and 5 is provided with a boss *a¹* at each end through which extends the shaft *c*. The drum is supported on said bosses by radial arms *a²* one of said bosses having a pin or internal projection *a³* adapted to enter a spiral groove *c⁶* provided on the shaft *c*, so that if the drum is rotated it will move in a longitudinal direction along the shaft. The movement of the drum is effected by the gearing *e* arranged on a suitable plate *e¹* screwed to one end of the box. The gearing comprises a main shaft *f¹* driven by the handle *f* or by any suitable motor. On this shaft is mounted a gear wheel *e²* which meshes with a pinion *e³* rigidly secured to a disk *e⁴* so as to rotate the latter when rotated from the main shaft. The disk *e⁴* is provided with a pin *e⁵* which on rotation is adapted to engage the slots or openings *e⁶* in a disk *e⁷* so that as the pin disk *e⁴* rotates, the pin *e⁵* thereon engages the slot *e⁶* and moves the slot disk *e⁷* quarter of a revolution, and on further rotation the pin *e⁵* leaves the said slot to engage the next succeeding slot. Thus the disk *e⁴* makes four revolutions for one revolution of the slot disk *e⁷* thus effecting an intermittent rotation of the latter.

An elongated pinion *e⁸* is secured at one end to the disk *e⁷* so as to rotate therewith and is supported at the other end in a suitable bracket *e⁹* attached to the interior of

the box. The intermittent movement imparted to disk *e⁷* and elongated pinion *e⁸* is transmitted to the drum *a*, the latter being provided with a toothed ring or wheel *a⁴* at one end which is always in mesh with the elongated pinion *e⁸*. Thus as the latter is rotated the drum is also rotated, and at the same time is moved along the shaft *c* by reason of the projecting pin *a³* engaging the spiral groove on said shaft *c*.

The film *b* may be affixed to the drum *a* in any suitable manner; in Fig. 4, this fixing is effected by making the drum *a* conical or tapered for receiving an internally tapered cylinder *b¹* which is slid onto the drum, in a similar manner to that adopted in fixing a phonographic cylindrical record to its drum or carrier. The film *b* is secured to the cylinder *b¹* by pasting or otherwise, so that it may be easily removed for developing. Another method of attaching the film to the drum may be effected by providing the film or the like with a transverse rod or rail *b²* of wood or other suitable material at each end thereof, the rods *b²* being square in cross section and of the same size. The drum *a* in this case is cylindrical and is provided with a longitudinal opening or slot *a⁵* so that when the film *b* is placed around the drum the square rods *b²* at the ends thereof meet and together fit into the slot *a⁵* in which position they may be retained by pivoted cam levers or the like *b³* mounted on the interior of the drums, and bearing against the outside edges of said strips as shown in Figs. 5 and 6. In this manner the film or the like is held tightly around the drum and the two ends thereof in meeting make a very close joint which is not apparent when the pictures are observed through the magnifying lens. The film is removed by releasing the cam levers *b³* from engagement with said rods *b²* and taking out the rods from the slot in the drum.

The front of the box or casing *c* carries the lens *h* and the rotary photographic shutter *g*, the latter being actuated from the gearing *e* when the main shaft is rotated through an intermediate pinion *g¹* in mesh with the gear wheel *e²* engaging with another pinion *g²* mounted on the spindle *g³*. The other end of the spindle is supported in a bearing and carries a bevel wheel *g⁴* engaging with another bevel wheel *g⁵* mounted on a short spindle *g⁶*, the latter being adapted to receive the shutter *g* which may be detachably secured thereto.

The lens *h* through which the photographs are taken is mounted in a gate piece *h¹* provided with grooved side edges which engage an opening in the front side of the box as shown in Fig. 2, so that said gate piece may be easily inserted, or removed to enable another to be fitted. The front of the box

or casing is closed in a light tight manner by a sliding piece *i* fitting in grooves as shown in Fig. 3, and is provided with an aperture *i*¹ through which the photographs are taken. Said aperture *i*¹ may be closed when the apparatus is not in use by rocking a shutter *i*² on the inner side which is operated from the exterior by turning the lever or arm *i*³ lying close against the surface of the sliding piece *i*. A knob *i*⁴ is provided for enabling the sliding piece to be conveniently withdrawn.

The rotary shutter *g* is in the form of a disk provided with an opening *g*⁷ and is held on the spindle *g*⁶ by the thumb screw *g*⁸ or other suitable means, so as to rotate therewith, said opening coming opposite the lens *h* and aperture *i*¹ in the sliding piece *i* during the rotation of the shutter *g*. A suitable view finder *d*⁵ is situated in the lid *d*¹ of the casing and a carrying handle *d*⁶ is provided on the lid; the apparatus may be used on a stand or tripod as is usual with hand photographic cameras.

In taking the photographs, it is only necessary to focus the subject, open the aperture *i*¹ by moving the shutter *i*², and to rotate the operating handle *f* so that the shutter in rapidly rotating will expose the sensitized film each time the opening in said shutter comes opposite the lens *h*. Thus the photographs will be taken in quick succession on the film and owing to the intermittent rotation and at the same time longitudinal movement in the direction of the arrow *W* in Figs. 1 and 2, the photographs are taken in a helical path around the drum commencing at the end *X* and terminating at the end *Y*. The rotation and movement of the drum at each step of its intermittent movement is effected during the time the lens *h* is covered by the shutter *g* so that when the opening *g*⁷ is opposite the lens the drum is stationary and the film is then exposed. The mechanism is so arranged that the operating handle is rotated clockwise, which is the more convenient direction. Having taken the photographs, the film is removed from the drum in the dark room, and is developed and fixed in the usual manner to produce the negative and during this treatment the aforesaid wooden rods or rails attached to the film become detached, thus leaving the film quite flat. A print can then be taken from the negative, on any suitable paper and in any appropriate manner, the paper being provided at each end with the transverse wooden or other rods. The paper on which the pictures or finished photographs appear is mounted on the drum and secured in position in a similar manner to that described with reference to retaining the film in position.

When the apparatus is to be used for obtaining the kinematographic effect, the gate

piece *h*¹ is replaced by a similar gate piece *h*¹ provided with a plain opening *j* in lieu of the lens. Further the gate piece does not completely close the opening in the front side of the box, but allows a certain space *j*² to be left. The circular shutter *g* is replaced by a segmental shutter *k* which is preferably of the shape as shown in Fig. 8^a and is secured to the shaft by the thumb screw *g*⁸ or other suitable means so as to rotate therewith. The sliding piece or front *i* used when taking the photographs is replaced by another sliding piece *k*¹ on which is adjustably mounted a tube carrying a magnifying lens *k*². This sliding piece *k*¹ is also provided with an opening *k*³ to admit light to the interior of the apparatus. In order that the picture can be sufficiently illuminated to be seen clearly through the magnifying lens *k*¹, a condensing lens *k*⁴ is pivotally mounted on said sliding piece *k* adjacent to the opening *k*³ therein. The position of the condensing lens *k*⁴ can be moved to concentrate the light from a window, or lamp on to the space or position where the pictures appear opposite the gate aperture *j*.

When the photographs are taken on the film they would appear the reverse way up if viewed from the front of the apparatus with the operating handle on the left hand side, *i. e.*, looking into the aperture *i*¹ from the position shown in Fig. 1, but the pictures would appear the correct way up when the apparatus is turned round and placed in the position shown in Fig. 8 which is regarded as a plan. This brings the operating handle to the right hand side and the front of the apparatus now becomes the top so that the pictures are observed by looking downward in a vertical direction. After the photographic print has been taken from the film and affixed to the drum so that the pictures are presented the correct way up to the observer, with the apparatus in the observing position, Fig. 8, the commencement of the pictures occurs at the opposite end of the drum. It is therefore necessary that the drum should be moved past the observing lens in the opposite direction and at the same time it is essential for convenience to rotate the handle in the clockwise direction. To enable the drum to be moved in the opposite direction when "observing" and at the same time allowing the handle to be operated with the observer's right hand and in a clockwise direction, the shaft is provided with right and left hand helical grooves or threads *c*⁸ and *c*⁹ respectively preferably meeting at the center of the shaft. Therefore if the right hand groove or thread *c*⁸ be used when "taking" the drum will be moved in the direction of the arrow *W* in Figs. 1 and 2, the drum will be remounted on the shaft to engage the

left hand helical groove or thread c^9 when "observing," so causing the drum to be moved past the lens in opposite direction, as indicated by the arrow Z in Fig. 8.

- The magnifying lens l^1 can be adjusted to suit the sight of the observer, and the enlarged pictures or photographs appear to the eye when the drum carrying the print is moved past the aperture in the manner 10 already described. Whereas the circular or disk shutter g during the greater part of its rotation completely closes the lens h when taking the photographs, the segmental shutter used when "observing," permits of 15 light entering the openings j^2 and k^3 practically the whole time, and simply prevents the actual movement of the drum when changing from one position to another from being observed.
- 20 The shutters for "taking" and "observing" are illustrated in Figs. 1^a and 8^a respectively, and each form is provided with a hole for attachment to the spindle and also with an additional opening g^9 for engaging a key or 25 pin carried on the spindle so as to rotate therewith. A thumb screw g^8 fitting on a screw threaded end of the spindle holds the shutter in position.

The pictures may be projected on to a small 30 screen by using a transparent positive film not provided with transverse strips. For this purpose the drum is replaced by a glass cylinder or drum l having at one end a toothed ring or wheel a^4 and adapted to be 35 rotated and moved in the manner above described. The transparent positive is placed around the glass drum l and is adapted to be secured thereon in any suitable manner, for example by gumming just the ends of the 40 film or otherwise securing on the cylinder so that they meet to form a close joint. A small electric lamp l^1 is placed in the interior of the drum by screwing it in to a hole in the center of the shaft c after the drum 45 has been placed on the shaft so that it is in a line with the center of the lens l^2 which in this case may be an enlarging lens mounted on a gate piece l^3 similar to the aforesaid gate piece. As the pictures travel past the 50 lens the light from the lamp will project them through said lens on to a small screen l^4 carried by supports l^5 secured on the front of the box or casing. The screen may be conveniently mounted on a sliding piece having 55 a large opening to allow the rays to reach the screen l^4 . Within the electric lamp is arranged a reflector to throw the whole of the light on to the picture opposite the lens. Current is supplied to the lamp from 60 any suitable source l^6 and is conducted thereto through insulated wire within the shaft c . The segmental shutter is preferably employed when projecting.

Various modifications may be made with-

out departing from the nature of the invention for example, instead of employing separate gate pieces as aforesaid a sliding piece moving in a longitudinal direction may be used, which carries the lens for taking, the aperture and opening for observing, and the lens for projecting, so that each may be brought opposite a permanent opening in the front of the box or casing when desired. Again a sliding front may be employed which carries the apertures for taking, lenses 75 and the like for observing, and the opening for projecting, said front piece also being adapted to slide longitudinally into the proper position for the respective operations.

What we claim and desire to secure by Letters Patent of the United States is:—

1. In kinematographic apparatus the combination of a drum, provided with a transverse opening therein, a photographic band in the form of a sheet, transverse rails or rods attached to said film and adapted to meet and fit in said transverse opening in the drum when the film surrounds the latter, retaining means on said drum for engaging said rails or rods on the film, a stationary shaft for said drum or carrier, and means moving said drum along said shaft to enable successive photographs to be taken or observed.

2. In a kinematographic apparatus the combination of a stationary shaft provided with a helical groove or thread, a film supporting drum or carrier mounted on said shaft, a projection carried by said drum for engaging said helical groove, a gear wheel attached to said drum, an elongated pinion continuously in mesh with said gear wheel and means for imparting an intermittent rotation to said elongated pinion to cause 100 the drum to intermittently rotate and travel along said shaft.

3. In a kinematographic apparatus the combination of a box or casing, a helically grooved stationary shaft means for retaining said shaft in position, a film supporting drum mounted on said shaft, bosses on said drum, a projection secured to one of said bosses to engage said helical groove, a gear wheel attached to said drum, an elongated pinion continuously in mesh with said gear wheel, a Geneva stop motion for intermittently rotating said pinion, gearing for operating said Geneva stop motion, and means carried by the apparatus whereby the latter is adapted for taking, observing, and projecting.

4. In kinematographic apparatus the combination of a stationary shaft provided with right and left handed helical grooves, a drum or carrier mounted on said shaft, a photographic film or band surrounding said drum, means carried by said drum for en-

- gaging one of the helical grooves when "taking" and for engaging the other groove when "observing", a gear wheel attached to said drum an elongated pinion continuously in mesh with said gear wheel, means for intermittently rotating said elongated pinion, and means for enabling the photographs to be taken or to appear successively in a helical path around said film or band.
5. In a kinematographic apparatus the combination of a box or casing, a lid or cover hinged thereto, a double front portion forming part of said box, interchangeable slides or covers for fitting to each part of
10. 5. In a kinematographic apparatus the combination of a box or casing, a lid or cover hinged thereto, a double front portion forming part of said box, interchangeable slides or covers for fitting to each part of
15. said double front portion, interchangeable shutters for fitting between each part of said double front portion, and adapted to coöperate with said interchangeable slides or covers whereby the apparatus is adapted
20. for taking, observing, and projecting gearing for operating said shutters, a film supporting drum or carrier mounted within said box or casing and means for moving said drum to enable successive photographs
25. to be taken or observed.
6. In a kinematographic apparatus the combination of a box or casing, a lid or cover hinged thereto, a double front portion forming part of said box, a sliding piece, a
30. taking lens mounted thereon, means for fitting said sliding piece to the inner part of said double front, a sliding front piece provided with an aperture, means for fitting said front piece to the outer part of said
35. double front so that the aperture in the sliding front piece is opposite said "taking" lens, a rocking shutter mounted on the sliding front piece for closing said aperture, a film supporting drum or carrier mounted
40. within said box or casing, means for intermittently moving said drum in a rotary and longitudinal direction, a rotary shutter having an opening therein, means for operating said rotary shutter so as to expose the film
45. when the drum is stationary and to completely close the aperture and lens during the movement of said drum.
7. In a kinematographic apparatus the combination of a box or casing, a lid or
50. cover hinged thereto, a film supporting drum or carrier, means for imparting an intermittent rotary and longitudinal movement to said drum, a double front portion forming part of said box or casing, a sliding
55. piece having an aperture therein, means for fitting said sliding piece to the inner part of said double front portion so that an open space in addition to the aperture is provided, a sliding front piece, a magnifying
60. lens mounted thereon, means for fitting said sliding front piece to the outer part of the double front portion, means mounted on said sliding front piece for concentrating a beam of light on to the photographs as they
65. pass the magnifying lens, a segmental shut-
- ter and means for moving said shutter to obstruct or cover the pictures during the actual movement of the drum.
8. In a kinematographic apparatus, the combination of a film supporting device, a flat photographic film or band, means secured on said film to detachably retain the film in a cylindrical manner on said device, a gear wheel secured to said film supporting device and means continuously engaging said gear wheel adapted to move said supporting device to enable successive helically arranged photographs or pictures to be taken or observed.
9. In a kinematographic apparatus, the combination of a box or casing, a drum or carrier mounted therein, a flat photographic film or band, means carried by said film adapted to detachably hold the same tightly around said drum so as to possess a degree of rigidity, a stationary shaft for said drum or carrier, a gear wheel secured to said drum, and means continuously engaging with said gear wheel adapted to move said supporting device to enable successive helically arranged photographs to be taken or observed.
10. In a kinematographic apparatus, the combination of a drum or carrier, a photographic film or band in the form of a flat sheet, mechanical means for detachably affixing said sheet to the drum whereby no relative movement between said sheet and drum can take place, a stationary shaft for said drum or carrier, a gear wheel secured to said drum, and means continuously engaging with said gear wheel adapted to move the drum in a rotary and longitudinal direction along said shaft to enable successive photographs to be taken or observed.
11. In a kinematographic apparatus the combination of a drum or carrier, a photographic film or band, means provided on said film for engaging said drum, means on said drum for retaining the film in position, a stationary shaft for said drum or carrier, a gear wheel secured to said drum and means continuously engaging said gear wheel adapted to move said drum along said shaft to enable successive helically arranged photographs to be taken or observed.
12. In kinematographic apparatus the combination of a drum provided with a transverse opening therein, a photographic band in the form of a sheet, traverse rails or rods attached to said film and adapted to meet and fit in said transverse opening in the drum when the film surrounds the latter, retaining means on said drum for engaging said rails or rods on the film, a stationary shaft for said drum or carrier, and means moving said drum along said shaft to enable successive helically arranged photographs to be taken or observed.
13. In a kinematographic apparatus, the

combination of a detachable helically grooved non-rotating shaft, a film supporting drum or carrier mounted thereon and engaging with said helical groove, a gear wheel secured to said drum, and means continuously engaging said gear wheel to simultaneously rotate and longitudinally move the drum along said shaft to enable successive helically arranged photographs to be taken or observed.

14. In a kinematographic apparatus the combination of a box or casing, interchangeable means arranged to be carried by the apparatus whereby the apparatus is adapted for "taking" "observing" and "projecting," a drum or carrier mounted within said box or casing, a stationary shaft for supporting said drum, a photographic film or band surrounding said drum a gear wheel secured to said drum, and means continuously engaging said gear wheel to intermittently and simultaneously rotate and longitudinally move said drum.

15. In a kinematographic apparatus the combination of a box or casing, interchangeable slides for fitting to said box whereby the apparatus is adapted for "taking" "observing" and "projecting," some of said slides having suitable apertures therein, suitable lenses attached to some of said slides, interchangeable shutters, means for operating said shutters, a film supporting drum, a stationary helically grooved shaft

for supporting the drum, a gear wheel secured to said drum, and means continuously engaging with said gear wheel to intermittently and simultaneously rotate and longitudinally move said drum on said shaft.

16. In a kinematographic apparatus the combination of means for supporting a photographic film in a cylindrical manner, a stationary shaft along which the said supporting means is adapted to be moved, means for imparting an intermittent rotary and longitudinal movement to said supporting means, and means arranged within said supporting means for projecting the photographs of the film on to an external screen.

17. In a kinematographic apparatus, the combination of a film supporting device a hollow stationary shaft, of electrical conducting material for the drum, means for imparting an intermittent rotary and longitudinal movement to the drum along said shaft, electrical means on said shaft for projecting the photographs on to an external screen, and an insulated electrical conductor housed in said shaft and connected to said electrical projecting means.

In testimony whereof we affix our signatures in presence of two witnesses.
